UNITED STATES PATENT OFFICE.

FRANKLIN P. LITTLE AND WILLIAM H. McDONALD, OF ALBANY, ASSIGNORS
TO JOSEPH A. POWERS, OF TROY, NEW YORK.

RHEOSTAT.

SPECIFICATION forming part of Letters Patent No. 340,449, dated April 20, 1886.

Application filed January 22, 1886. Serial No. 189,355. (No model.)

To all whom it may concern:

Be it known that we, FRANKLIN P. LITTLE and WILLIAM H. McDONALD, of the city of Albany, and State of New York, have invented an Improvement in Rheostats, of which the following is a specification.

This invention relates to an improvement in rheostats, whereby naked wire can be made use of, and there is no covering that can be injured by the heat and the wire becomes cool very rapidly, and we provide insulating material that will not be injured by the heat developed by the resistance.

In the drawings, Figure 1 is a sectional plan of the rheostat without any case. Fig. 2 is a vertical section of the rheostat and case with only three coils of wire; and Fig. 3 is a section in larger size, showing the insulating material.

20 We make use of a frame, K, in the form of crosses united together by the permanently-riveted wires n, that pass from one cross to the other and through holes in the same, the ends being riveted up.

25 We prefer to use German-silver wire for the coils of the rheostat, and we wind such coils around the range of wires n, first, however, applying to each wire n a strip of asbestos paper or other fire-proof and electric insulator, as shown at t, Fig. 3, the wires being at a slight distance apart and insulated by the asbestos paper, which also is fire-proof

and is not injured by the heat developed in the rheostat.

30 After the first layer of resistance-wire is wound around the range of wires n and secured, we insert through holes in the crosses K the second set of wires, o, and apply the asbestos paper to the same, and then wind the second layer of resistance-wires around the same, and proceed until a rheostat of the proper resistance is made up, and this is placed upon a central stem, P.

The case T, that surrounds the rheostat, is of perforated sheet metal, to allow the air to circulate in cooling the rheostat, and it is fastened by pins or screws upon the edges of the base Q, entering bayonet slots in the case, so that the case can be removed easily to give access to the rheostat.

35 We claim as our invention—

The cross-frames K, having connecting wires and fire-proof electric insulating material upon their surfaces, in combination with the coils of wire wound around the ranges of connecting-wires, substantially as set forth.

40 Signed by us this 4th day of January, A. D. 1886.

F. P. LITTLE.
WM. H. McDONALD.
